REMOVABLE PLUG FOR OPENINGS IN
METER CASINGS

Albert J. Wayman, East Palestine, Ohio

Application January 7, 1952, Serial No. 265,311

7 Claims. (Cl. 220—55)

1

This invention is concerned with a removable closure for unused openings in the casings or housings of electrical apparatus, such as the casing of an electric meter.

In various electrical devices it is customary to provide a number of tapped holes in the enclosing casing or housing for the purpose of effecting the connection of one or more electric cables to the device by means of screw-threaded connectors. Frequently the casing is provided with more openings than are required, and it becomes necessary to close the unused openings in order to protect the device from the effects of moisture or other material that might enter through the openings, and to prevent the theft of current through the openings.

An object of the present invention is to devise a closure which may be quickly and easily applied and removed.

Another object is to provide for the locking of the closure in position and to prevent unauthorized removal of the closure.

Another object is to embody a sealing gasket within the closure to seal the opening against the entrance of moisture.

Still another object is to provide a closure which may be applied and removed without disconnecting the power from the cables entering the casing.

My invention is illustrated in the accompanying drawing, in which Figure 1 is a fragmentary sectional view of a portion of a casing or housing of an electrical device showing the removable closure mounted in position to close an unused threaded opening in the casing, and Figure 2 is a sectional view of the plug or closure, similar to the showing in Figure 1, and showing the use of a shield or guard extending over the end of the locking screw.

Referring to the drawing, a fragmentary section of the casing of the electrical device is shown in Figure 1. This may be the casing of an electric meter, or the casing of an electric switch or other device. The casing is formed of a side wall 1 and a bottom wall 1a. The open top is closed by a suitable cover plate, not shown. The casing is provided with a number of openings 2 through which connecting cables may be introduced into the casing, only one opening being shown in Figure 1. Each opening is surrounded by a sleeve 3 integrally formed with the casing wall. The sleeve 3 is provided with internal threads 3a for receiving the threaded end of a connector secured to a cable to be introduced through the opening 2. While the drawing shows

the internally threaded sleeve 3 extending to the outside of the casing, in some cases most of the sleeve 3 will be located inwardly of the casing.

Where an opening is not used, I provide a plug-like closure for the opening, as shown in Figure 1. The closure plug is formed of a tubular shank portion 4 closed at its outer end by a rounded head 4a which is formed with an annular flange portion 4b extending over the outer end of the sleeve 3. The flange portion 4b is provided with a flat annular face which extends outwardly from shank 4 and seats upon the flat annular face on the outer end of the sleeve 3. The shank 4 has a smooth outside cylindrical surface of a diameter somewhat less than the internal diameter of the sleeve 3 so that the shank may be introduced into the threaded opening quickly and without a screwing operation.

The tubular shank 4 is provided with a thickened portion 4c internally thereof, and a locking screw 5 is threaded through this thickened portion at an acute angle to the plane of the flat face of the flange portion 4b, as shown in the drawing. The screw 5 is located near the inner end of the shank 4, and the end of the screw engages the thread 3a to lock the plug in position to close the opening. The locking screw is inclined so that its axis passes substantially through the upper part of the opening 2. By arranging the locking screw in this manner, it is possible to tighten the screw by means of a screw-driver introduced through the open side of the casing in a direction inclined somewhat to the vertical. In this way it is not necessary for the screwdriver to extend laterally into the casing from the opening where it might interfere with the electrical parts enclosed within the casing. It is possible to install my improved closure plug without disconnecting the electric power from the connections inside of the casing.

For the purpose of sealing the unused openings against entrance of moisture, an annular recess 4d is formed in the flat face of the annular flange portion 4b adjacent the shank 4, and this recess is filled with a suitable permanently plastic sealing compound 6. Each plug, when sold on the market, may have its individual supply of sealing compound already applied in the recess 4d, or the compound may be applied at the time the plug is installed in a casing. Preferably, the quantity of compound applied to the plug would be in excess of that required to fill the recess 4d, and some of the excess would be forced into the outer end of the sleeve 3 to form a better seal.

Injury to the internal threads of the sleeve 3

by the screw 5 may be prevented by providing a guard extending over the end of the screw, as shown in Figure 2. This guard may be formed of a thin strip of metal 7 bent into U-shape, one leg of the U extending along the upper surface of the thickened portion 4c and having a hole through which the screw 5 passes, and the other leg extending on the outside of the shank 4 to cover the end of the screw 5. The guard 7 is deformable by the end of the screw to lock the plug in the opening, but it prevents direct engagement of the hardened end of the screw with the threads 3a.

It is not essential that the shank portion 4 of the plug be tubular, since this portion may be formed solid except for a cavity sufficiently large to receive the screw 5 and the end of the guard piece 7. The construction shown is preferred for economy in the use of metal.

The shank of the plug must be sufficiently long so that screw 5 may be turned by a screw-driver inserted through the opening 2 from the opposite side of the wall 1.

I claim:

1. A closure for closing internally threaded openings in casings of electrical devices comprising a plug having a shank portion formed of a smooth cylindrical outer surface of a diameter slightly smaller than that of said opening, an enlarged head portion on one end of said shank having an annular flange presenting a flat annular face extending radially outward from the outer surface of said shank, the other end of said shank having a cavity formed therein, a locking screw threaded in a hole extending from said cavity to the outside of said shank on an axis arranged at an acute angle to the plane of said annular flange, said flange having an annular recess formed in said flat annular face, and plastic sealing compound filling said annular recess.

2. A closure for closing internally threaded openings in casings of electrical devices comprising a plug having a shank portion formed of a smooth cylindrical outer surface of a diameter slightly smaller than that of said opening, an enlarged head portion on one end of said shank having an annular flange presenting a flat annular face extending radially outward from the outer surface of said shank, the other end of said shank having a cavity formed therein, and a locking screw threaded in a hole extending from said cavity to the outside of said shank on an axis arranged at an acute angle to the plane of said annular flange, said flange having an annular recess formed in said flat annular face.

3. A closure for closing internally threaded openings in casings of electrical devices comprising a plug having a shank portion formed of a smooth cylindrical outer surface of a diameter slightly smaller than that of said opening, an enlarged head portion on one end of said shank having an annular flange presenting a flat annular face extending radially outward from the

outer surface of said shank, the other end of said shank having a cavity formed therein, and a locking screw threaded in a hole extending from said cavity to the outside of said shank on an axis arranged at an acute angle to the plane of said annular flange.

4. A closure for closing internally threaded openings in casings of electrical devices comprising a plug having a shank portion formed of a smooth cylindrical outer surface of a diameter slightly smaller than that of said opening, an enlarged head portion on one end of said shank having an annular flange presenting a flat annular face extending radially outward from the outer surface of said shank, the other end of said shank having a cavity formed therein, a locking screw threaded in a hole extending from said cavity to the outside of said shank on an axis arranged at an acute angle to the plane of said annular flange, and a thin metallic strip having one end thereof connected to the head-end of said screw and the other end arranged to cover the outer end of said screw.

5. A closure according to claim 1 and including a thin metallic strip having one end thereof connected to the head-end of said screw and the other end arranged to cover the outer end of said screw.

6. In combination, a casing adapted to house an electrical device and having an opening formed therein, an internally threaded sleeve surrounding said opening and formed integrally with said casing, a closure for said opening comprising a plug having a smooth cylindrical shank portion extending into said sleeve and an enlarged head portion on the outer end of said shank portion, said head portion having an annular flange presenting a flat annular face adapted to seat upon the flat outer end face of said sleeve, the inner end of said shank having a cavity formed therein, and a locking screw threaded in a hole extending from said cavity to the outside of said shank on an axis arranged at an acute angle to the plane of said annular flange.

7. A structure according to claim 6 wherein the annular flange of said plug has an annular recess formed in the flat annular face thereof, and including a plastic sealing compound filling said annular recess and forming a moisture seal between said flange and the outer end of said sleeve.

1. A closure for closing internally threaded openings in casings of electrical devices comprising a plug having a shank portion formed of a smooth cylindrical outer surface of a diameter slightly smaller than that of said opening, an enlarged head portion on one end of said shank having an annular flange presenting a flat annular face extending radially outward from the outer surface of said shank, the other end of said shank having a cavity formed therein, and a locking screw threaded in a hole extending from said cavity to the outside of said shank on an axis arranged at an acute angle to the plane of said annular flange.

2. A closure according to claim 1 and including a thin metallic strip having one end thereof connected to the head-end of said screw and the other end arranged to cover the outer end of said screw.

3. A closure according to claim 1 and including a thin metallic strip having one end thereof connected to the head-end of said screw and the other end arranged to cover the outer end of said screw.

4. A closure for closing internally threaded openings in casings of electrical devices comprising a plug having a smooth cylindrical shank portion extending into a sleeve and an enlarged head portion on the outer end of said shank portion, said head portion having an annular flange presenting a flat annular face adapted to seat upon the flat outer end face of said sleeve, the inner end of said shank having a cavity formed therein, and a locking screw threaded in a hole extending from said cavity to the outside of said shank on an axis arranged at an acute angle to the plane of said annular flange.

5. A structure according to claim 4 wherein the annular flange of said plug has an annular recess formed in the flat annular face thereof, and including a plastic sealing compound filling said annular recess and forming a moisture seal between said flange and the outer end of said sleeve.
